UNITED STATES PATENT OFFICE.

HARVEY S. COVER, OF SOUTH BEND, INDIANA.

DESIGN FOR A DUST-PROTECTOR.

SPECIFICATION forming part of Design No. 27,962, dated December 7, 1897.

Application filed October 6, 1897. Serial No. 654,298. Term of patent 7 years.

To all whom it may concern:

Be it known that I, HARVEY S. COVER, a citizen of the United States, residing at South Bend, in the county of St. Joseph and State 5 of Indiana, have invented and produced a new and original Design for Dust-Protectors, of which the following is a specification, reference being had to the accompanying drawings, forming part of this specification, in 10 which—

Figure 1 is a perspective view of a dust-protector, showing my new design therefor. Fig. 2 is a rear view thereof; and Fig. 3, a vertical section on line 3 3, Fig. 2.

15 As shown in the drawings, the leading feature of my design consists in an ovoid-conoidal-shaped cover to fit over the nose and

mouth of the wearer, having a flat end A, in which are a series of concentric openings B around a central opening C. At the sides 20 are rings D, and on one side is a round valve-shaped object E and below it a projecting L-shaped object F. The base or inner edge of the device is beaded or cushion-shaped, as at G. Within the device is a reticulated 25 crescent-shaped division H, seen only from the rear.

What I claim is—

The design for a dust-protector substantially as herein shown and described.

HARVEY S. COVER.

In presence of—

JAMES DU SHANE,
EDWARD F. DUBAIL.
